AIRSCREW

John Davenport Siddeley, and Hamilton Nell
Wylie, Coventry, England, assignors to Sir
W. G. Armstrong Whitworth Aircraft, Limited,
Whitley, Coventry, England

Application December 13, 1935, Serial No. 54,338
In Great Britain July 3, 1934

11 Claims. (Cl. 170—159)

This invention relates to airscrews such as have composite blades.

The main object is to provide an improved air-screw which will not be liable to flutter, will have 5 high aerodynamic efficiency, and will be of low weight.

In ordinary airscrews the blades are liable to vibrate owing to rapid fluctuations of air pressure. In such vibrations the blades bend mainly 10 about transverse axes lying in the direction of the width of the blade. The bending is usually accompanied by twistings which cause variations in pitch angle and consequently in air pressure, and the fluctuation in pressure is liable to synchronize with the bending so as to increase it. This gives rise to conditions of forced vibrations 15 which cause rough running and subject the blade material to increased stress, and which in certain circumstances may be so pronounced as to amount to perceptible or even destructive "flutter" of the blades.

It is known that the twisting of the blades is mainly due to inertia forces which oppose the sudden bending of the blade under a momentary 20 increase in pressure, and oppose its spring back when the momentary increase of pressure abates and which cause it to overshoot the mean position. The inertia forces on any short length of blade act through the centre of mass of that 25 length whereas the resistance of the blade to bending acts along what is known as the flexural axis. If the centres of mass of each short length of blade could be arranged to lie along the flexural axis the inertia forces would not cause twisting of the blade, but in present-day blades of 30 aerofoil section and of one material, or when built up from more than one material according to common practice, the centres of mass are to the rear of the flexural axis. This disposition 35 causes fluctuations in aerodynamic pressure which increase any vibration which may have started in the blades.

Now, according to the main feature of the invention, a composite air-screw blade has its 40 leading portion formed of material having a greater density than that of material which forms, alone or with one or more lengths, or is part of, the trailing portion, and the leading portion serves also mainly or entirely for the 45 support of the blade. For instance, the leading portion may be of steel or aluminium alloy and the trailing portion of wood, bakelite or other non-metallic substance of a lower density than that of the leading portion. In this way the 50 centre of mass of any short length of blade may

be arranged to be close to or actually on the axis of flexure, and it may even be slightly forward thereof. Thus the twisting due to inertia can be reduced or eliminated, or caused to damp out vibrations that may have started, the blade being 5 one which will rigidly resist change of form of its cross-section.

In the accompanying drawings illustrating various constructional forms of air-screw blade embodying the principles of the invention:—

Figure 1 is a plan of a composite metal and wood blade with parts in section; Fig. 1a is a continuation of the blade shown in Fig. 1;

Figure 2 is an elevation of the leading portion 15 of the blade as viewed from the back thereof; Fig. 2a is a continuation of the blade shown in Fig. 2;

Figures 3, 4 and 5 are cross-sections on the 20 lines III—III, IV—IV and V—V, respectively, of Figure 1;

Figure 6 is a fragmentary cross-section through 25 a blade showing a further method of joining the leading and trailing portions;

Figure 7 is a plan of a preferred form of composite blade; Fig. 7a is a continuation of the 30 blade shown in Fig. 7;

Figure 8 is a part-sectional elevation thereof taken from the rear; Fig. 8a is a continuation of the structure shown in Fig. 8;

Figures 9, 10, 11 and 12 are cross-sections taken 35 on the lines IX—IX, X—X, XI—XI and XII—XII of Figure 7, respectively; and

Figure 13 is a cross-section taken on the line 40 XIII—XIII of Figure 7 but indicating a small modification.

Like numerals indicate like parts throughout the drawings.

In the arrangement illustrated in Figures 1 to 45 5, the leading portion 2 of the blade consists of a steel tube which is originally of uniform outside diameter but of tapering bore so that the wall thickness increases from the tip inwards to the root. The tube is pressed to the appropriate form, the section being circular at the root 3 and changing gradually along its length to form the forward parts of an aerofoil as shown by the sections in Figures 3 to 5. Towards the tip the width is reduced by cutting the rear edge only at 4. The root 3 is formed to be carried by the hub in any known manner—for example, as shown in Figure 1, a sleeve 5 having a flanged end 5a may be fixed to the root 3 by welding, the end of the sleeve being serrated at 6 to provide an increased length of weld and to improve the distribution thereof.

The trailing portion 8 is formed of wood in the 55

following manner. A number of individual parts 9, 9, Figures 1 and 5, are transversely arranged with respect to the leading portion, the grain of each part extending across the width of the blade. 5 Each part consists of a piece of relatively hard wood, such as mahogany, having a substantially rectangular cross section over most of the length and having a circular cross section at the forward end which thus forms a peg 10. The pegs 10 pass through clearance holes 11, 11 in the rear edge of the metal portion 2 and are driven into and fixed, as by gluing, in holes provided in a longitudinally-extending member 12 (which may be of hard wood) housed in the rear of the metal 15 tube 2 and fitting it closely for a substantial distance towards the tip, as shown by Figure 5. The width of the rectangular portions of the parts 9, 9, is such that they contact with each other, as shown in Figure 1. Towards the tip of the blade a continuous length of wood 9a is used, this having a continuous peg portion 10a which extends with clearance through a slot 11a in the rear edge of the leading portion and fits in a corresponding slot in the internal member 12. 20 Also, towards the root a continuous length of wood 9b is used, this being secured as hereinafter described. The parts 9, 9, 9a, 9b together form a continuous connecting rib or fin 90 for the reception of fairing parts later described. 25

30 The internal member 12 is anchored to the root 3 so that the pull due to centrifugal force may be taken by the root fittings without being imposed directly on the blade. As shown in Figures 1 and 4 the internal member 12 is clamped by rivets 13, 13 between metal plates 14, 14 extending towards the root and welded as shown at 15 in Figure 3 to a part-sleeve portion 16 adapted to fit inside the root 3 and to act as a reinforcing plate where metal screws 17, 17 pass through the root for a purpose later described. This part-sleeve is secured by welding to the root.

35 The trailing portion 8 is completed by shaped fairings 18, 18 of wood having the grain running substantially parallel to the length of the blade 40 and secured to the connecting rib 9, 9, 9a, 9b by adhesive such as glue in known manner.

45 The centrifugal pull due to the trailing portion is taken by metal plates or brackets of which three are shown. The internal one 19 is welded to the rear of the metal portion 2 near its root and the outer ones 20, 20 are secured to the metal portion 2 and the part-sleeve 16 by the screws 17, 17. The metal plates or brackets are secured to the wood laminae by bolts or tubular rivets 21, 50 21 which pass through the laminae and plates and clamp these all tightly together. The joints may be reinforced by adhesives.

55 In the alternative arrangement illustrated in Figure 6, the leading portion 2 and root are solid and preferably of a light alloy such as aluminium or magnesium alloy. The means of fitting the connecting rib 90 to the leading portion 2 consists in undercutting the rear edge of the latter as shown at 22 and the width of the undercut groove 60 is preferably stepped down towards the tip. The connecting rib 90 is mainly in short transverse sections as above described, these being driven tightly into each length of groove which they fit. Where the thickness becomes very small at the 65 tip undercutting may be dispensed with and the wood may be held in position relative to the metal portion by thin metal sheathing of known type preferably connected only to the metal part so as to permit slight longitudinal movement relative thereto. The wooden fairings 18, 18 are at-

5 tached on each side of the connecting fin 90 as in the previous arrangement. The greatest thickness of the leading portion 2 is near its rearward edge and its thickness diminishes towards the leading edge which is rounded. Because the 10 mean thickness is relatively near the rearward edge, the centre of mass is also relatively near the rearward edge.

15 In the modification shown by Figures 7 to 11 the leading portion 2 essentially comprises a substantially C-shaped part 23 which is symmetrical towards its root and bent to be of partial aerofoil section over the rest of its length towards the tip. It is formed with inwardly-extending flanges 24, 24 which are bent to provide spaced 20 flanges 25, 25. Actually, in the arrangement illustrated in Figures 9 to 11, the flanges 24, 25 are provided by separate angle parts welded at 26 to the ends of the C-shaped portion 23, instead of being formed integrally therewith. Alternatively, as shown by Figure 13, they could be replaced by Z-shaped pieces 27 welded at 26 to the C-shaped part 23, these pieces providing the flanges 24 and 25.

25 In the present instance the hub sleeve 5 is shaped to fit in the interior of the root of the C-shaped part, as indicated at 28 in Figure 11 particularly, and one wall of the sleeve is secured by rivets 29 to the packing piece 30 and to the flanges 24. The hub sleeve 5 carries an 30 anti-friction thrust bearing 31 disposed adjacent its flange 5a to facilitate feathering of the blade.

35 The connecting rib 90 of the trailing portion is in this case built-up of three laminae, an internal one 32 glued between two laminae 33. The latter, when of wood, preferably have the grain extending in the direction of the width of the blade, and the internal one 32 preferably has the grain extending lengthwise of the blade. This 40 connecting rib 90 extends for part of the blade length between the flanges 25, 25 into the interior of the leading portion 2 and is wedged in the leading portion, as shown by Figures 9 and 13, by means of a wooden bar 34. Towards the root 45 the intermediate portion 90 is cut away, as indicated at 35 in Figures 7 and 10, and is secured as by rivets 36 to the plates 37 which extend between the flanges 25. The root end of the connecting rib 90 and the plates 37 are secured to the flanges 25 by the rivets 39, and the connecting 50 rib 90 is directly clamped against the flanges 25 by the rivets 39. Filling-in pieces 40, 40 may be fitted over the lines of the rivet 39.

55 Where the edges of the C-shaped part 23 come near together towards the tip the flanges 25 may be brought together, as from 25a onwards, and the wood fairings 18 be secured directly to the outside of them, the rib 90 being discontinued, as indicated at 90a. Preferably the flanges 24, 24 are cut short at 25b and extended by a T-piece 124 which is curved towards the rear edge of the blade, the edges of part 2 meeting to form the rear edge at the tip at 200.

60 Preferably the tip of the blade is loaded near its leading edge so that the centre of mass will be well forward thereof. Instead of the loading being applied by a thickening of the metal there, use is preferably made of metal strips 42 welded to the metal of the leading portion 23 before the 65 latter is completely closed at its rear edge 200.

65 In any of the arrangements described provision may be made for slight relative longitudinal movement between the leading and trailing portions to accommodate expansion which may occur 70

cur at times, as, for instance, by the rivets 39 in Figure 7 being an easy fit in the flanges 25.

By means of the invention light efficient airscrews can be built which will not be liable to flutter. Furthermore, such blades can be attached to the hub, by means which allow feathering of the blade, to give very satisfactory service.

What we claim as our invention and desire to secure by Letters Patent of the United States 10 is:—

1. A composite airscrew blade built up from lengths of different materials on its leading and trailing portions, said leading portion being rigidly attached to a supporting metal sleeve, 15 the material of which said leading portion is constructed being of greater density than the material of which said trailing portion is constructed, and brackets secured to said leading portion in the vicinity of said sleeve, said trailing portion being secured to said brackets.

2. A composite airscrew blade built up from lengths of different materials on its leading and trailing portions, said leading portion serving substantially entirely for the support of the blade, 25 and the material of which said leading portion is constructed being of greater density than the material of which said trailing portion is constructed.

3. A composite airscrew blade having different 30 materials forming its leading and trailing portions, respectively, the material of which said leading portion is constructed being of greater density than the material of which said trailing portion is constructed, and the parts being arranged such that the centre of mass of any short 35 portion of the blade is close to the transverse centre of the blade.

4. A composite airscrew blade consisting of a hollow metal leading portion and a laminated trailing portion, the trailing portion being constructed of material having a lower density than the material of the leading portion, said leading portion serving substantially wholly for the support of the blade.

45 5. A composite airscrew blade comprising a trailing portion formed of wooden laminations, and a leading portion constructed of material having a greater density than the material of the trailing portion, one of the laminations of said trailing portion having its grain extending transversely of the blade and another having its grain extending longitudinally thereof, said leading portion serving substantially wholly for the support of the blade.

55 6. A composite airscrew blade comprising a trailing portion formed of wooden laminations and a leading portion constructed of material having a greater density than the material of the trailing portion, one of the laminations of

said trailing portion having its grain extending transversely of the blade and another having its grain extending longitudinally thereof, and said leading portion serving substantially wholly for the support of the blade.

5

7. A composite airscrew blade comprising a trailing portion formed of wooden laminations glued to one another and a hollow leading portion formed of metal, one of said laminations having its grain extending transversely of the blade, and 10 means for securing said one lamination to the leading portion.

8. A built-up airscrew blade having a hollow metal leading portion and a trailing portion formed of material having a lower density than 15 the material of the leading portion, said trailing portion comprising a plurality of laminations, one of said laminations extending into the interior of said leading portion, and means for securing said one lamination to said leading portion. 20

9. A composite airscrew blade comprising a hollow metal leading portion, spaced parallel flanges extending from the rearward edges of said leading portion, a trailing portion, said trailing portion being constructed of material having less density than the material of which the leading portion is constructed, said trailing portion having a part extending between said flanges, and means securing said extending part 30 to said flanges.

10. A composite airscrew blade having a hollow metal leading portion, spaced parallel flanges carried by the rearward edges of said leading portion, a trailing portion, said trailing portion being constructed of material having lower density than the material of which the leading portion is constructed, said trailing portion comprising a plurality of laminations glued to one another, one of said laminations being built up 40 of a plurality of parts glued to one another and extending into the interior of said leading portion, and means for clamping said one lamination against said parallel flanges.

11. A composite airscrew blade having a hollow metal leading portion, spaced parallel flanges carried by the rearward edges of said leading portion, a trailing portion, said trailing portion being constructed of material having lower density than the material of which the leading portion is constructed, said trailing portion comprising a plurality of laminations glued to one another, one of said laminations extending into the interior of said leading portion, and means 50 for clamping said one lamination against said parallel flanges.

JOHN DAVENPORT SIDDELEY.
